(57) **CLAIM**

The ornamental design for a driver adapter for hexagonal socket head fasteners, as shown and described.

DESCRIPTION

FIG. 1 is a perspective view of a driver adapter for hexagonal socket head fasteners, showing my new design;

FIG. 2 is a front view thereof with a rear view being a mirror image;

FIG. 3 is a left side view thereof with a right side view being a mirror image;

FIG. 4 is a top view thereof; and,

FIG. 5 is a bottom view thereof.
